CLAIM

The ornamental design for an electrical stove, as shown and described.

DESCRIPTION

FIG. 1 is a top, front, right-side perspective view of an electrical stove;

FIG. 2 is a front elevation view of the electrical stove;

FIG. 3 is a rear elevation view of the electrical stove;

FIG. 4 is a left-side elevation view of the electrical stove;

FIG. 5 is a right-side elevation view of the electrical stove;

FIG. 6 is a top plan view of the electrical stove; and,

FIG. 7 is a bottom plan view of the electrical stove.

The broken lines are shown for the purpose of illustrating parts of the article that form no part of the claimed design.

1 Claim, 5 Drawing Sheets
